UNITED STATES PATENT OFFICE

2,391,201

ADJUSTABLE WINDOW GUARD

Joe F. Smith, Memphis, Tenn.

Application July 27, 1944, Serial No. 546,799

4 Claims. (Cl. 160—223)

This invention relates to stock sized adjustable window guards of that type which has a hinged end, which, when the guard is in place in the window, is secured rigidly and locked to prevent unauthorized removal of the guard, and which may be unlocked to allow escape through the window, as in case of fire, or for window cleaning or removal to another location.

Window guards are known which have locking features, but these ordinarily are made to exact measurement to fit the particular window frames with which they are to be used. There are also expandable features known, but their methods are complicated and of expensive construction and are outside the reach of many low income purchasers.

The inventor has been manufacturing window guards for ten years and selling them all over America. This invention is a result of a long experience, calculated to remedy the various difficulties experienced, some of most frequent occurrence.

Elimination of errors in measuring and installing. Dealers ordering guards will often make a mistake (as small as $\frac{1}{16}$ inch) in measuring the window span. Confusion, rebuilding, returning and reshipping and cancellation results.

Enable dealers to carry guards in stock. Window frames and sashes are normally built in stock sizes ranging from twenty inches by twenty inches to forty-two inches by thirty-six inches. Installing alters these sizes and as a result final sizes are different by fractions of an inch, creating thousands of different sizes. Consequently guards are now largely being tailor-made to fit individual conditions.

Provide adjustment. Window guards need to be singly adjustable, at least two inch adjustment in width would allow a stock size for each stock sized window, and the hundreds of variations from these stock sizes could be cared for within the adjustment.

Allow for mass production and reduced cost. Meeting exact measurements has resulted in slow tailor-made production. By reducing requirement to a given number of stock guards, assembly line methods can be employed; interchangeable parts manufactured in mass can be effected; off season employment can be provided; and the usual American mass production principle will be instrumental in greatly reducing the cost to all purchasers.

Locking features. The simplicity of this invention allows the use of the ordinary padlock for locking requirement, at the same time ef-

fecting a hinge which rigidly expands the guard into place and also making the guard adjustable for many different sized windows.

The objects of the present invention are:

To provide a simple and efficient window guard;

To eliminate errors in measuring, ordering and installing window guards;

To provide a window guard which can be carried in stock by manufacturers and dealers, thereby eliminating tailor-made trade practices which are costly and keep the price of window guards beyond the reach of low income purchasers;

To provide an adjustable window guard having provision for substantially symmetrical adjustment of its opposite sides;

To provide a guard through mass production and use of interchangeable parts which will permit year-round manufacture, and simplify and combine many features now unobtainable.

Fig. 1 is an elevation showing a guard in place in the window frame.

Fig. 2 is an enlarged fragmentary plan showing one end of the guard.

Fig. 3 is a similar view showing the opposite end of the guard; and

Fig. 4 a fragmentary elevation showing the end of the guard shown in Fig. 2.

Both Figs. 1 and 2 show the inner side of the guard.

Referring now to the drawing in which the various parts are indicated by numerals:

11, 13 are opposite portions of a window frame between which portions the guard is disposed.

The guard comprises top and bottom rails 15, 17, ends 19, 21, and grill rods 23 carried at their upper and lower ends by the top and bottom rails respectively.

The top and bottom rails are straight members, preferably of angle iron and of substantially equal length. Each has holes at spaced intervals for reception of the grill rods 23, 24, which may be of any desired cross section, but as here shown, are square. The grill rods have central portions of equal length terminating in shoulders which abut against the under and upper surfaces of the upper and lower rails to prevent longitudinal displacement of the rods. In the present illustrations, diagonally opposite corners of the rods are cut away from the rod ends inward, the flattened portions 23A thus formed terminating to form the shoulders. The holes in the rails 15 and 17 are punched to conform to the outer ends of the rods and are of the shape of the end of the rod 23, in Fig. 2. Additionally both upper and lower rails are punched adjacent

their ends to receive at their locking ends rivets 25 and 26, and at their opposite ends clamping bolts 27 and 28.

The end members 19 and 21 are also preferably of angle iron, and comprise vertical portions, designated by the end member numerals 19 and 21, which portions seat against the window frame members 11 and 13, and upper and lower legs 31, 33, and 35, 37, respectively, which slidably engage the upper and lower rails 15 and 17. The legs 35 and 37 of one end member are provided with slots 39 and 41, (the slots in the upper leg 35 only being shown) which respectively receive the bolts 27 and 28, and the grill rod 24 and permit shift of the end member 21 relatively to the rails 15 and 17, and may be clamped in any position of adjustment by tightening the bolts 27 and 28. These bolts are on the inside of the angle iron rails which permit their being loosened or transferred from the outside.

The lower leg 33 of the opposite, or locking end member is shortened so that it does not reach to the rod 23 and is provided with a single slot corresponding to the slots 39 of the opposite end member, and is slidably and turnably secured by the rivet 26 to the lower rail 17.

The upper leg 31 of the end member 19 has a slot 43 adapted to shiftably receive the rivet 25 carried by the upper rail, one side of the slot having notches 43A into any one of which the rivet 25 may be shifted. These notches are spaced one-half of any major adjustment which is to be made in the width of the guard, that is if a guard is for use, in a thirty inch window it may be narrowed for use in a twenty-nine inch, or widened for use in a thirty-one inch window, the three notches spaced at one-half inch intervals effecting one-half of the desired one inch decrease or increase in width at that side of the guard by shift of the rivet one notch either way from the center notch, and the balance of the decrease or increase be made at the opposite slidably adjustable side, and any minor variation in width be cared for by such slidably and incrementally adjustable side. The leg 31 is also provided with additional holes 45, 47, 49 and 51 at respective notch spacing from the proximate one of the notches 43A.

The upper rail is also provided with a pair of holes 53 and 55 which register with underlying holes of the leg when the rivet is in one of the notches 43A and the leg extended straight beyond the rail 15. As shown, the holes in the upper rail register with the holes 49 and 51 of the leg, 57 is a padlock having a staple 59, here shown as engaged in these registering holes. The leg 31 preferably extends inward past the first of the grill rods 23, the vertical side of the leg angle and a portion of the horizontal side being cut away so that the extending portion 31A seats against the rod 23 when the leg is locked, and acts as a lever or handle in hinging the guard for extension into place or breaking down for removal from place.

With the lock removed the leg 31 of the end member may be laterally shifted to disengage the rivet 25 from that one of the notches 43A in which it is engaged, and the end member shifted inward or outward, as the case may be, to decrease or increase the width of the guard. If for instance the decrease desired in the width of the guard from that shown is one inch, a shift to a notch one-half inch away would establish the total shift for that side of the guard and the remaining decrease in width of the guard be

accomplished by loosening the bolts 28 and 27 and shifting the end member 21 approximately the same amount, this maintaining the symmetrical positioning of the rods 23 and 24 with respect to the window, the slidable adjustment of the end 21 permitting any necessary over or under shift of that end to compensate for irregularities or minor differences of the window frame width.

With the width of the guard established the guard may be broken about the rivet 25 as a hinge to permit the removal or replacement of the guard of established width in the frame, this movement being indicated by the dotted position 31B, in Fig. 2. Incidentally, if the upper rail be an angle iron the vertical leg of the angle iron must be cut away at 15A to allow such shift. When the end member 19 is swung back into alignment with the rails 15 and 17 and the staple 59 of the lock engaged, the end 31A of the upper leg 31 of the end member rests against the edge of the rod 23 and effectually prevents disengagement of the rivet from the notches.

With this construction, top and bottom rails 25 may be made up in quantities during slack seasons as may be the rods and the end members 19 and 21, it being particularly noted that any height of end member may be used for the top and bottom rails so that it is only necessary to select from stock a top rail and a bottom rail of desired length, an end member 19 and an end member 21 of desired height, and such number of rods as may be necessary for the particular length of top and bottom rail selected.

In assembling, the rods may be slipped downward into the holes in the bottom rail until their shoulders seat, the top rail be then positioned over the rods and slipped down on them until it seats on the shoulders of the rod, the end member 19 placed between the rails and the rivets 25 and 26 inserted and headed to secure the end member 19 to the rails. These may be shouldered rivets, as disclosed in Fig. 4, but in any event are not so tightly set up as to clamp the legs to the rails and prevent shift and adjustment. Bolts 27 and 28 are then placed through the holes in the upper and lower rail and the complementary slots in the end members and the guard is ready for use.

Should it be desired, both ends of the guard may be made slidably adjustable in conformity with the end 21 and the locking feature omitted.

It will be understood that the shoulders formed on the bars are for the purpose of preventing vertical displacement of the bars relatively to the rails, and for that purpose that where flat bars are used twisting of such bars immediately below the upper and above the lower rail will provide the necessary shoulder. In any case, riveting or welding is eliminated, making for further economy in manufacture.

I claim:

1. An adjustable window guard, for use in windows having frames of differing sizes, said guard including longitudinally disposed rails and vertically disposed ends adjustable in the direction of the length of said rails; a first of said ends being constrained for longitudinally sliding movement and the second for sliding and pivotal movement, and means for clamping said first end to said rails in any position of adjustment, said second end including a horizontal portion shiftably contacting one of said rails, said portion having therethrough a longitudinally extending slot and a plurality of holes and said rail carry-

ing a pivot pin extending through said slot, said slot being notched along one side at equal intervals for engagement, by transverse shift, with said pin and establishment of defined pivotal locations, said holes being spaced apart at equal intervals with said notches, said rail having holes therethrough adapted to register with holes of said end portion when said pin is in notch engagement, and a lock having a staple adapted for engagement through said registering holes.

2. An adjustable window guard, for use in windows having frames of differing sizes, said guard including longitudinally disposed rails and oppositely disposed ends, each including a vertically disposed portion and horizontally disposed leg portions slidably under and overlying said top and bottom rails respectively, and being adjustably shiftable in the direction of the length of said rails, a first of said ends being constrained for sliding movement and the second for sliding and pivotal movement, and means for clamping said first end to said rails in any position of adjustment, said second end having through one of its leg portions a longitudinally extending slot and a plurality of holes and the adjacent said rail carrying a pivot pin extending through said slot, said slot being notched along one side at equal intervals for engagement, by transverse shift, with said pin and establishment of defined pivotal locations, said holes being spaced apart at equal intervals with said notches, said rail having holes therethrough adapted to register with holes of said end portion when said pin is in notch engagement, and a lock having a staple adapted for engagement through said registering holes.

3. An adjustable window guard, for use in windows having frames of differing sizes, said guard including longitudinally disposed rails and oppositely disposed ends, each rail end including a

vertically disposed portion, and horizontal leg portions slidably under and overlying said top and bottom rails respectively, and being adjustably shiftable in the direction of the length of said rails, a first of said ends being constrained for sliding movement, and the second for sliding and pivotal movement, the legs of said first end being longitudinally slotted and having through said slots, bolts carried by said rails to effect clamping engagement therewith in any position of adjustment; said second end having through one of its said leg portions a longitudinally extending slot and the adjacent said rail carrying a pin slidably disposed through said slot; the other said leg portion having therethrough a longitudinally extending slot and a plurality of holes therethrough and the rail adjacent thereto carrying a pivot pin extending through said slot, said slot being notched along one side at equal intervals for engagement by transverse shift with said pin and establishment of defined pivotal locations, said holes being spaced apart at equal intervals with said notches, said rail having holes therethrough adapted to register with holes of said end portion when said pin is in notch engagement, and a lock having a staple adapted for engagement through said registering holes.

4. An adjustable window guard including upper and lower rails and end members forming a frame, both of said end members being shiftable in the direction of the length of said rails to vary the width of said guard, means for establishing step by step positioning of one said end, and locking means for securing said end in a selected one of said positions, and means for clamping the opposite said end in any positioning necessary to effect with the first said end the desired width of frame.

JOE F. SMITH.
